UNITED STATES PATENT OFFICE

MARTIN ROSEN, OF CHICAGO, ILLINOIS, ASSIGNOR TO SUN-GOODS CORPORATION, OF CHICAGO, ILLINOIS, A CORPORATION OF ILLINOIS

METHOD OF PACKING LOOSE PARTICLES OF FOOD

Original application filed August 24, 1927, Serial No. 215,004. Divided and this application filed April 27, 1928. Serial No. 273,179.

The invention relates to a novel and improved method of packing loose particles of food, such for example, as raisins, nuts, hard candies, a mixture of nuts and raisins, and the like.

The invention contemplates certain novel and improved steps in the formation of a package for packing loose particles of food, and the like.

10 The package formed by the novel and improved method is characterized by being compact and neat in appearance, and all of the walls of which except one wall thereof being transparent whereby the contents there-
15 of may be readily inspected from the outside thereof, and by having a withdrawable flap or apron, which is adapted to facilitate the dispensing of the contents of the package therefrom. This results from the novel
20 method employed in packaging the contents.

According to the invention the package is formed from a single piece of transparent material of any desired shape, such for example, as "glassine" paper, or the like, and
25 a stiff cardboard backing, the shape and size of said backing being that of the finished package. The piece of transparent material has formed therein a pocket or depression, the size and shape of which is that of the
30 finished package, the loose particles of food are then placed within said pocket, and one corner or side of said transparent material is folded over said particles of food. The stiff cardboard backing is then placed over
35 said food particles and the folded over corner, and the remaining corners or sides of said transparent sheet are then folded over on said stiff backing, thus completely and fully enclosing said food particles. The
40 package may then be sealed by securing the said folded over corners or sides of said transparent sheet to said stiff back, which may be done in several well known ways. I have found, however, the following method
45 for securing the folded over corners to the stiff backing to be the most advantageous. I provide a label or seal gummed on the inner side, which label or seal is of the same size and shape as the stiff back, and is applied thereto to seal the package.

This application is a division of my application filed August 24, 1927, Serial No. 215,004.

To these and other ends, the nature of which will be readily understood as the invention is hereinafter disclosed, said invention consists in the improved method hereinafter more fully described, illustrated in the accompanying drawings, and more particularly pointed out in the appended claims.

In the accompanying drawings forming a part of this application and in which like numerals designate like or similar parts throughout the several views:

Fig. 1 is a top plan view of the wrapper employed in carrying the invention into effect, said wrapper being shown in position on a form and ready for the first step in the series of steps in forming and filling the package;

Figs. 2 to 7 inclusive, illustrate the successive steps of filling and forming the package;

Fig. 8 illustrates the finished package; and

Fig. 8, illustrates the finished package; and the upper flap pulled out for assisting in dispensing the contents from the package.

In carrying the invention into effect, a package is produced which is filled with loose particles of food, such for example, as raisins, nuts, hard candies, a mixture of nuts and raisins, and the like, one wall of which package is relatively stiff, and the remaining walls of which are formed from a single piece or sheet of transparent material, such for example, as "glassine" paper, or the like, said transparent material having three corners or sides thereof folded over and secured to the outer side of said stiff wall, and the remaining corner or side being disposed between the contents of the package and the inner side of said stiff wall, whereby the said last-mentioned corner or side may be pulled out and assist in dispensing the contents from the package.

In the method contemplated of forming the package, a wrapper 10, of transparent material, such for example, as "glassine" paper, or the like, is depressed in its central portion to form a pocket or depression 11, therein,

the shape of said pocket being that of the desired shape of the finished package, and the depth thereof being that of the depth of the finished package. This pocket or depression 11, may be formed in one of several ways, however, I have found the following method of forming the pocket 11, to be the most practical. I employ a frame or member 14, provided with a recess or depression 12, the size and shape of which is that of the size and shape of the finished package, and the depth of which is that of the thickness of the finished package. The size and shape of said member 14, being sufficient to accommodate the wrapper 10, thereon, as shown in Fig. 1. A member 15, provided with a plunger 13, may be hinged to said member 14, at one side thereof, the member 15, being adapted to be swung to bring the plunger 13, into the recess 12, as shown in Fig. 2, the shape and size of said member 15, being preferably the same as that of the member 14, for a purpose to be hereinafter described.

The first step then in the filling and forming of the package is to place the wrapper 10, on the member 14, the said wrapper being centered over the depression or recess 12, as shown in Fig. 1. The member 15, is then swung about its pivot to bring the plunger 13, to its lowermost position in the recess 12, depressing the central portion of the wrapper 10, to form the pocket 11 therein, the corners or sides of the wrapper being held flat against the upper surface of the member 14, by the member 15, upon which the plunger 13, is mounted, thus the turning or curling up of the corners of the wrapper is prevented in the formation of the pocket or depression in the wrapper.

It will be noted that during the downward movement of the plunger 13, in forming the depression or pocket 11, the corners or sides of the wrapper 10, are free to move inwardly towards the depression in the member 14. Thus the danger of the paper or wrapper 10, tearing during the formation of the pocket 11, is eliminated.

When the pocket has been formed and the plunger withdrawn, the loose particles of food 16, are then placed in the pocket and tamped down, said pocket being filled just up to the level of the top thereof, as shown in the drawings. Then one of the corners or sides of the wrapper 10, the corner 17, for example, is folded over and disposed on top of the food particles as shown in Fig. 4. The next step is to place a stiff sheet of cardboard 18, or the like, directly on top of the food particles 16, and of course over the folded over corner 17, of the wrapper, as shown in Fig. 5, the size and shape of the cardboard 18, being the same as the size and shape of the finished package.

After the cardboard 18, has been placed in position on top of the food particles, the re-

maining corners or sides of the wrapper 10, are folded over and pulled tightly to lie flat on the sheet 18, thus completely enclosing the food particles. The last-mentioned corners or sides may be secured to the sheet 18, in one of several ways in order to seal the package, however, I have found the following method for securing the said corners to said sheet to be the most practical.

I provide a label or seal 19, said label being gummed on the inner side, and is applied to the sheet 18, and over the folded over corners as shown in Fig. 7. This seal is adapted to secure the corners of the wrapper 10, to the stiff sheet 18, and to thus seal the package. This seal or label may be of any desired shape or size, but is preferably the same size as the sheet 18, and may be provided on the outer side thereof with suitable advertising matter or the like. The finished package may then be lifted out of the recess 12, in its fully assembled condition. To aid in lifting the assembled package out of the recess 12, the sheet 18, may be provided on one side thereof with an extension or ear 20, having a perforation therein for supporting the package on a display stand or the like. The member 14, is provided with a small depression 21, provided adjacent the recess 12, for receiving the ear or extension 20, as shown in the drawings.

The corner or side 17, which is disposed between the food particles and the inner face of the cardboard 18, is adapted to be pulled out when it is desired to get to the contents of the package, and as is apparent from an inspection of Fig. 9, of the drawings, said corner is adapted to assist in dispensing the contents from the package, said corner acting as a trough or apron over which the food particles are adapted to pass.

It will of course be understood that where packages of different shapes are desired, the wrapper will be correspondingly varied. While I have shown one way in which the invention may be carried out, it will be readily understood that the principles of the invention may be utilized in other ways and through other forms of mechanism than those suggested herein, the selection of a specific embodiment being determined more particularly by the exigencies of use or the particular wishes of the user, and I reserve the right to make all such changes in and adaptations of the construction of my invention as fairly fall within the scope of the accompanying claims when broadly construed.

I claim:

1. The series of steps in the method of forming a package, which consists in forming a pocket in a wrapper, then placing loose particles of food in said pocket, then folding one corner of said wrapper over the said food particles, then placing a stiff sheet over said folded over corner and said food particles,

and then folding the remaining corners of said wrapper over said stiff sheet.

2. The method of forming a package, which consists in forming a depression in a wrapper, then filling said depression with loose particles of food, then folding one corner of said wrapper over said particles of food, then placing a stiff sheet over said folded over corner on said food particles, then folding the remaining corners of said wrapper over said stiff sheet, and then applying an adhesive strip to the outer folded corners and the stiff sheet.

3. The series of steps in a method of forming a package, which consists in forming a square pocket in a wrapper, then filling said pocket with loose confections, then folding one corner of said wrapper over and down on top of said loose confections, then placing a square piece of stiff cardboard of substantially the same size as the pocket on top of the confections, then folding over the remaining corners of the wrapper on top of the cardboard, and then securing the said last mentioned folded over corners of the wrapper to the cardboard.

4. The series of steps in the method of packaging loose particles of food, which consists in forming a pocket in a wrapper, then placing loose particles of food in said pocket, then folding some of the corners of said wrapper over the said food particles, then placing a stiff sheet over said folded over corners and said food particles, then folding the remaining corners of said wrapper over said stiff sheet, and then securing said folded over corners last mentioned to said sheet.

In testimony whereof I affix my signature.
MARTIN ROSEN.
